UNITED STATES PATENT OFFICE.

HUBERT ANGEBRANDT, JR., OF TOLEDO, OHIO.

GLUE DISSOLVER AND RETAINER.

1,055,506.

Specification of Letters Patent. Patented Mar. 11, 1913.

Application filed December 1, 1911. Serial No. 663,327.

To all whom it may concern:

Be it known that I, HUBERT ANGEBRANDT, Jr., a citizen of the United States, residing at Toledo, in the county of Lucas and State 5 of Ohio, have invented certain new and useful Improvements in Glue Dissolvers and Retainers; and I do declare the following to be a full, clear, and exact description of the invention, such as will enable others skilled 10 in the art to which it appertains to make and use the same.

This invention relates to improvements in glue dissolving and retaining apparatus.

One object of the invention is to provide 15 an apparatus of this character having a non-steam contact dissolving and retaining mechanism whereby the dissolved glue may be retained and kept warm until drawn from the apparatus.

20 A further object is to provide a glue dissolving apparatus having a glue dissolving pan adapted to be readily removed from the apparatus when desired.

With these and other objects in view the 25 invention consists of certain novel features of construction and the combination and arrangement of parts as will be more fully described and claimed.

In the accompanying drawings; Figure 1 30 is a central vertical section of my improved glue dissolving apparatus; Fig. 2 is a top plan view thereof; with the lid or cover removed.

In the embodiment of the invention, I 35 provide a main tank or casing 1 which may be provided with supporting legs 2 or supported in any suitable manner. In the tank 1 and spaced a suitable distance above the bottom thereof is a transverse partition 3 which forms in the lower portion of the tank a water compartment 4 which is adapted to receive the water formed by the condensation of the steam employed in dissolving the glue and by means of which the 45 dissolved glue is kept warm until drawn from the apparatus. The partition 3 forms the bottom of a dissolved glue compartment 5 and said partition or bottom inclines from one side of the tank toward the opposite side 50 thereof in which side at the lowest part of the partition or bottom 3 is arranged a glue discharging faucet 6.

The top of the dissolved glue compartment 5 is formed by a partition 7 having 55 therein a central opening 8 the walls of which are bent upwardly to form an annu-

lar flange 9. The partition plate 7 inclines from the edges of the opening 8 downwardly toward the sides of the tank 1 to which the edges of the partition are secured. The 60 outer edges of the partitions 3 and 7 are preferably provided with depending annular flanges secured to the inner surface of the sides of the tank in any manner to form a fluid tight joint or connection between 65 these parts.

Removably arranged in the upper portion of the tank and supported upon the partition 7 is a glue dissolving pan 10 of less diameter than the inner diameter of the tank 70 and having its side walls inclined inwardly and its bottom 11 inclined from the outer edges thereof downwardly toward a central opening 12, the walls of which are bent downwardly to form an annular flange 13 75 which is adapted to fit closely within the flange 9 whereby the pan 10 is supported and held in a concentric position in the tank.

Means for preventing the entrance of steam into the compartment 5 or into the 80 pan 10 is herein shown in the form of interlocking flanges on the bottom of the glue pan 10 and the upper face of the partition 7. While these flanges are shown as integral 85 with the partition and pan, it is obvious that they are not necessarily so but may be secured thereto in any suitable manner.

In addition to the flange 13 the bottom of the glue dissolving pan 10 has also formed thereon an annular downwardly extending 90 drip deflecting ring or flange 13' which is spaced a suitable distance from the flange 13 and engages or is disposed adjacent to the outer side of the flange 9 on the partition 7, said drip deflecting flange preventing any 95 drip from passing between the flanges 9 and 13 and into the melted glue compartment 5. By thus arranging the ring or flange 13' it will be seen that any steam condensing on the sides of the glue dissolving pan 10 and running down the sides and around the bottom thereof will be deflected by the flange 13' and caused to flow down over the partition 7 from which the same is carried off in a suitable manner hereinafter described. 100 The arrangement of the partition 7 and bottom of pan 10 facilitates the passage of the water of condensation to the means therefor hereinafter to be described, and the drip flange 13 prevents all danger of the water 105 entering the compartment.

The opening 12 in the bottom of the pan

is covered by a screen 14 through which the dissolved glue drips into the dissolved glue compartment 5 arranged below the partition 7. On the upper edge of the glue dissolving pan 10 is arranged an outwardly projecting bead or flange 100 which when the pan is in place, engages the upper edge of a right angularly formed annular gutter or trough 15 secured to the inner side of the tank adjacent to its upper end as shown. The gutter or trough 15 forms a closure between the upper portion of the tank and the outer sides of the pan for a purpose hereinafter described. The pan 10 is provided with suitable handles 16 whereby the same may be readily lifted from the upper portion of the tank. The upper open end of the pan 10 and the upper end of the tank are closed by a conical shaped cover 17 having on its under side adjacent to its outer edge a depending flange 18 which fits into and engages the upper end of the tank as shown. The space between the partition 7 and the trough or gutter and surrounding the glue dissolving pan 10 forms a steam chamber 19 with one side of which is connected a steam inlet pipe 20 and with the opposite side of which, near the upper end thereof, is connected a steam discharging or pressure relieving pipe 21. On the inner side of the casing 1 over the end of the steam inlet pipe 20 is arranged a deflecting plate or hood 20' against which the steam strikes on entering the steam chamber 19 and by which the steam is deflected and caused to circulate uniformly around and through the chamber.

The partition 7 which forms the top of the dissolved glue compartment and the bottom of the steam chamber is slightly lower at one side and with said lower portion of the partition is connected the upper end of the condensed steam conducting or drain pipe 22 which extends downwardly through the dissolved glue compartment and the partition 3 to a point near the bottom of the water compartment 4 whereby the steam condensing in the chamber 19 is conducted to the water compartment. Also discharging into the water compartment 4 is a drain or condensed steam conducting pipe 23 which also passes upwardly through the compartment 5 and partition 7 and has its upper end connected with the gutter or trough 15 whereby any water of condensation accumulating on the inner side of the lid or cover 17 and dripping therefrom into the gutter is drained from the latter and conducted to the water compartment 4. The water of condensation thus conducted to the compartment 4 serves to keep the dissolved glue warm in the compartment 5. The water compartment 4 is provided in one side with an overflow pipe 24, near the upper end thereof or immediately below the

partition 3 as shown. The water compartment 4 is also provided in one side with a draw off faucet 25 by means of which the water may be removed from said compartment when desired.

By thus constructing and arranging the various parts of the apparatus the steam employed for dissolving or melting the glue in the pan 10 cannot reach or come in contact with the glue either while being dissolved or after the same has entered the dissolved glue compartment. By thus dissolving the glue without permitting the steam to come into contact therewith the quality of the glue is greatly improved. By thus constructing and arranging the various parts of the apparatus it will be seen that both the dissolving compartment or pan and the retaining compartment are combined or disposed in one tank thus providing a compact and efficient apparatus for the purpose described.

Attention is invited to the peculiar and advantageous arrangement of the interior construction of the apparatus and particularly to the manner in which the removable dissolving pan is supported by means of the partition 7 which serves the two-fold purpose of a cover for the dissolved glue compartment and a support for the dissolving pan which, when engaged with the partition 7 forms a steam tight connection between the pan and the dissolved glue compartment at the same time permitting the pan to be readily removed from the apparatus when desired. Further attention is invited to the arrangement of the warming feature of the apparatus wherein the melted glue in the compartment 5 is kept warm by the heat from the water of condensation dripping into the water compartment 4 and by such part of the steam as may pass from the steam chamber 19 through the drain pipe 22 to the water compartment.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is;

A glue dissolver comprising a closed tank having vertically spaced transverse partitions extending entirely across the tank and forming a water chamber and a dissolved glue compartment, the upper partition having an aperture therein, a glue dissolving pan disposed in said tank above said apertured partition with its side walls and bottom spaced from said tank and partition

respectively, the bottom of said pan having an aperture registering with the aperture in said partition, means connecting said pan bottom and apertured partition to form a fluid tight connection, a closure between the upper portion of the tank and pan whereby a steam tight space is formed around the side walls and bottom of said pan, means for admitting steam to said steam space and means for conducting the water of con-

densations from the steam space to the water chamber by which the dissolved glue is maintained in a heated state.

In testimony whereof I have hereunto set my hand in presence of two subscribing ¹⁵ witnesses.

HURERT ANGEBRANDT, JR.
